UNITED STATES PATENT OFFICE.

HERBERT CHARLES HUMPHREY SMYTH, OF LONDON, ENGLAND.

GOVERNOR FOR ELECTRIC-LIGHTING GENERATORS FOR MOTOR-CARS.

1,213,702.

Specification of Letters Patent. Patented Jan. 23, 1917.

Application filed October 26, 1915. Serial No. 58,078.

To all whom it may concern:

Be it known that I, HERBERT CHARLES HUMPHREY SMYTH, a subject of the King of England, residing at London, in the Kingdom of England, have invented a new and useful Governor for Electric-Lighting Generators for Motor-Cars, of which the following is a specification.

In motorcar lighting apparatus, the varying speeds of the car affect the output of the generating dynamo, and it is usual to provide means for controlling the output by opening or closing extra circuits through which current can flow, and also by opening and closing the external circuit of the dynamo at predetermined speeds of the armature.

It is the object of this invention to provide a centrifugal governor capable of being regulated, during working, for any speed and consisting of a single weighted lever arm pivoted to a support on the armature shaft and acting on a co-axial pin which slides in a stationary support in contact with multiplied leverage under adjustable spring-control for the purpose of making or breaking an electric circuit.

My invention is shown in the accompanying drawings, in which:—

Figure 1 is a side elevation, partly in section, of the device with the regulating spring omitted for the sake of clearness; Fig. 2 an end view of the stationary support for carrying the regulating spring and electrical contacts; Fig. 3, a diagram showing the positions of the electrical contact blocks arranged for breaking the electrical circuit at any predetermined speed; and Fig. 4, a diagram showing the arrangement of electrical contact blocks for making contact at any predetermined speed.

The regulating device is of the centrifugal type, that is to say it is operated by a weighted centrifugal lever W pivotally secured at H to a support D which is fixed to the armature shaft A of the generating dynamo; the end of the lever W, when subjected to centrifugal force, acts against a sliding pin or plunger which in turn presses against a lever L¹. The pin or plunger P is mounted in an aperture in a stationary support or plate F which also carries the said lever L¹ and other parts of the device. The lever L¹ is pivoted at H¹ radially toward the pin P and engages a lever L² near the pivot H¹. This lever L² is diametrically

pivoted at H² and is fitted with a pin E which carries the contact block B¹ which latter may be so disposed as to normally rest in contact with the stationary contact blocks B² and B³. The said levers L¹ and L² are kept pressed against the pin or plunger P by means of a coiled spring O, see Fig. 2, which with the end O¹ engages the lever L² and with the other end O² is fixed to the spindle Q on which the spring is coiled. The action of turning the squared end Q¹ of the spindle Q in the one direction or the other will either increase, or decrease, the tension of the spring, said spindle being locked by a screw S. It will be evident that when the weighted lever W is under centrifugal force, it presses against the pin P and by means of the multiplied leverage will shift the contact block B¹ and so break the electrical contact with the blocks B² and B³. The multiplied leverage is provided so as to overcome a far greater pressure at the contact blocks than can be produced under centrifugal force by the lever W on the pin P. The essential point about this construction is that the only part of this mechanism which is subjected to centrifugal force, is the weighted lever W. The regulating spring O does not move or revolve and therefore can be adjusted while the dynamo is in operation and as it is not attached to the shaft A, it is not affected by the heat generated in the armature.

The foregoing description refers to the arrangement of contact blocks B¹, B² and B³ when the device is required to break electrical contact at any predetermined speed of the armature shaft, but it will be clear from the alternative arrangement shown in Fig. 4 that when the contact block B¹ is normally held apart from B² and B³, the device will serve to make electrical contact when the predetermined speed is attained. It is to be naturally understood in both cases that the stationary blocks B² and B³ are insulated and form part of an electrical circuit.

I claim:

1. A centrifugal governor for electrical generators comprising a centrifugal lever rotating with the dynamo-shaft and separate contact-operating mechanism carried on an adjacent stationary supporting plate within the generator, said mechanism consisting of a sliding pin co-axial with the dynamo-shaft and movable in the station-

ary supporting plate, a radially disposed lever pivotally mounted on the latter and controlled at its free end by the said sliding pin, a contact lever pivoted diametrically opposite the radial lever and controlled thereby at its free end, a fulcrum-pin fast on the contact lever, an electric contact block seated on said fulcrum-pin, a pair of contact blocks fast on the stationary support 10 within the path of the fulcrumed contact block, and means for keeping the contact-operating mechanism in constant coöperation with the said centrifugal lever, as described.

15 2. In a centrifugal governor for electrical generators which comprises a single

weighted centrifugal lever carried by the dynamo-shaft and separate pin-operated multiplying lever mechanism on a stationary support for electrical contacts, the combination with said multiplying mechanism of a turnable adjusting spindle, an adjustable coil-spring retained on said spindle by one end and bringing the other end of said spring against the multiplying mechanism, 20 means for turning said spindle, and means for retaining same in an adjusted position, as described.

HERBERT CHARLES HUMPHREY SMYTH.
